UNITED STATES PATENT OFFICE

DAVID A. CUTLER, OF WOLLASTON, MASSACHUSETTS, ASSIGNOR TO ALFRED HALE RUBBER COMPANY, OF ATLANTIC, MASSACHUSETTS, A CORPORATION OF MASSACHUSETTS

DESIGN FOR A COMBINED SOLE AND HEEL

Application filed May 29, 1929. Serial No. 31,459. Term of patent 7 years.

To all whom it may concern:

Be it known that I, DAVID A. CUTLER, a citizen of the United States, residing at Wollaston, county of Norfolk, in the State of Massachusetts, have invented a new, original, and ornamental Design for a Combined Sole and Heel, of which the following is a specification, reference being had to the accompanying drawing, forming a part hereof.

Fig. 1 is a plan view of a combined sole and heel, showing my new design; and Fig. 2 is a cross-section on line 2—2 of Fig. 1.

I claim the ornamental design for a combined sole and heel, as shown.

This specification signed this 27th day of May, A. D. 1929.

DAVID A. CUTLER.
